UNITED STATES PATENT OFFICE.

SAM FRIEDMAN, OF ATLANTA, GEORGIA.

PRESSING MACHINE.

Application filed April 8, 1920. Serial No. 372,234.

To all whom it may concern:

Be it known that I, SAM FRIEDMAN, a citizen of the United States of America, residing at Atlanta, in the county of Fulton 5 and State of Georgia, have invented certain new and useful Improvements in Pressing Machines, of which the following is a specification.

This invention relates to an improvement 10 in pressing machines designed particularly for use in pressing clothing into proper shape following the cleaning of the same.

The main object of the invention is to construct an efficient presser in which the 15 labor incident to keeping up steam, and the use of the usual boiler and gas heating means is entirely avoided, and to place within control of the operator a simple and conveniently operated means for generating the 20 steam within the presser proper, and only in the quantity necessary for the particular operation.

Ordinarily in steam pressing machines, the goods, following the action of the presser 25 are damp, and require a subsequent drying operation. The present machine is designed to practically dry the clothes during the pressing operation, so that on leaving the presser the clothes are set in their pressed 30 form, and are practically dry and cool.

In the drawing:—

Fig. 1 is a perspective view of the improved machine.

Fig. 2 is a bottom plan view of the upper 35 pressing member, the cover portion thereof being removed, and the metallic plate partly broken away.

Fig. 3 is a top plan view of the bottom pressing plate, partly broken out.

Fig. 4 is a section on line 4—4 of Fig. 2.

Fig. 5 is a section on line 5—5 of Fig. 3.

Fig. 6 is a perspective detail showing slightly different forms of pressing members.

The improved pressing machine is here shown as comprising a table 1, supported on legs 2. The pressing elements comprise a lower pressing member 3, and an upper pressing member 4. These members are 50 shown, except in Fig. 6, as adapted for pressing coats and similar flat articles, though it is to be understood that these pressing members can have any appropriate formed meeting surfaces for the pressing of 55 special articles.

The upper pressing member 4 is of hollow form, the lower wall of which is preferably of rigid metal 5, formed throughout with a series of perforations 6. Pipes 7, in any appropriate number are arranged within the 60 hollow upper member 4, and these pipes are adapted to be supplied with water through a pipe section 8 leading through one side wall of the member, and beyond said side wall provided with a cut-off 9. The terminal of the pipe section 8 is adapted to receive a flexible hose or other conduit as 10 which may in turn be connected to a source of water supply, as an ordinary faucet. The pipes 7 are formed throughout with a 70 series of minute perforations 11, so that water admitted to said pipes under the control of the cut-off 9 will be discharged, through such perforations 11. The pipes 7 are preferably encircled by resistance coils 75 12, fed from a suitable source, as an ordinary incandescent light socket through wires 13 controlled by a switch 14 at the edge of the member. The heat thus developed is designed to be sufficient to convert 80 the minute streams or drops of water passing through the perforations in the pipes 7 into steam, so that the interior of the member 4 is, when in use filled with steam having an outlet through the perforations 6 of 85 the plate 5.

The lower member 3 is also hollow, the upper metallic plate 15 of such member having perforations 16 corresponding to the perforations 6 in the plate 5 of the upper 90 member. The interior space of this member is in communication through a pipe 17 with a suction device 18 located on the table 1 or convenient thereto. The suction device 18 is preferably electrically operated, being 95 for example in a parallel connection from the conductors 13. The switch for the suction operating connection, indicated at 19 is controlled by a foot lever 20 arranged at the lower end of a pedestal 21 depending 100 centrally from the table 1.

The pressing members 3 and 4 are on their meeting faces, that is the lower face of the upper member and the upper face of the lower member preferably covered with appropriate material, as 22, which may be cloth or the like and which is designed to directly engage the articles to be pressed. The lower member is supported on an up-right 23 rising from the table 1, and the up- 110

per member has hinged connection at 24 with the lower member, this hinged connection being preferably of the spring opening type so that the members are normally in opened or spaced relation. An operating pedal 25 through connections usual in this type of apparatus serves under pressure to force the members together into pressing contact.

In Figure 6, there is shown a slightly modified form of pressing members, in that the upper and lower members are flat. These pressing members are more readily adapted for pants and the like.

In use the operator, having applied the goods on the lower pressing member in smooth relation forces the upper member down by pressure upon the pedal 25 acting through suitable connections not necessary to show. The necessary pressure is maintained preferably by the operator standing on this pedal. The cut-off 9 is opened to allow water to enter the pipes 7, and the current turned on through manipulation of the switch 14. Steam is thus generated and the clothes subjected to such steaming during the pressing operation. Having maintained the pressure and steam application a sufficient period of time to complete the pressing of the particular article, the pedal 20 is operated setting the suction apparatus at work. At the same time the switch 14 is opened, and the cut-off 9 operated to cut off the water. The suction apparatus will draw steam through the goods and out a

discharge, tending to dry and cool the article 35 being pressed, and this in a comparatively short time.

The improved pressing machine generates its steam where and when needed, and in the quantity necessary for the particular work, 40 and at the same time the clothing on leaving the machine is cooled and dry and the smoothness gained by the pressing operation is therefore retained much longer than would be the case where such articles were 45 permitted to dry after being removed from the pressure.

What I claim is:—

The combination with a hollow movable buck of a clothes pressing machine, of 50 heating means therefor comprising an inlet pipe section mounted in one end wall of the buck, a plurality of pipes connected with and independently supplied with water through said section, said pipes relatively 55 diverging from each other from their connection with the inlet section and being in substantially the same horizontal plane, the lower portion of each pipe having spaced perforations, an electrical heating coil arranged about each pipe from end to end, and means for energizing said coils, whereby to convert the water in each pipe into steam and permit the escape of the steam through such perforations. 60

In testimony whereof I affix my signature. 65

SAM FRIEDMAN.
